ARTIST'S COLOR BOX

William Leslie Killik, London, England

Application September 17, 1935, Serial No. 40,886
In Great Britain October 10, 1934

9 Claims. (Cl. 41—4)

This invention relates to artists' color boxes.

As hitherto generally constructed, artists' color boxes have the lid of the box provided with two or more depressions of curved cross-sectional outline, which, when the lid is open, form a series of shallow troughs or wells in which the color may be mixed. An additional surface is sometimes provided in the form of a flat plate which is hinged to the body of the box so as to fold therein 10 and be covered by the lid when the box is closed.

With arrangements such as those just described it is found that in mixing the colors it is possible for one color to be readily contaminated by the other, and, further, when the box is closed any liquid which may be in the troughs or wells will run into the box and wet the cakes of color, brushes or other contents, in addition to causing the box to present a dirty and untidy appearance.

The present invention has for its object certain improvements designed to avoid the aforesaid objections, and according to which there is provided in the body of the box adjacent each receptacle for a cake of color, a surface on which color may be mixed.

In carrying the invention into effect, according to one form of the invention the box is provided with a longitudinal partition disposed in suitably spaced relationship to one of the side walls of the box and forming a receptacle for the brushes.

Extending from the said partition across the box to the other wall are suitably spaced partitions dividing the box into a series of compartments which are again divided by means of partitions extending transversely of the first partitions to provide cavities or receptacles for the cakes of color, the bottoms of the unoccupied parts of the compartments serving as surfaces on which the color can be mixed. Preferably the receptacles for the cakes of color are alternately arranged at the inner and outer end of the compartments.

According to another modification, two series of receptacles for cakes of color are provided, one series arranged along one side of the box and the other along the other side.

Running lengthwise of the box and extending between the aforesaid two series of receptacles is a space designed for the reception of brushes.

The arrangement of the receptacles for the colors and the surfaces for mixing the color may be the same in each series as that previously described, that is to say, the receptacles for the colors may be placed alternately at the inner and outer ends of the surfaces. In this case the surfaces may form part of independent trays which

are placed in staggered relationship one with respect to the other, their dimensions being such as to leave a space at one end to contain the cake of color.

The cakes of color may be of oblong rectangular, square, triangular, round or of any other desired outline.

According to a further modification, the box or container is of circular form, the cakes of color being radially disposed, the spaces between them forming surfaces upon which the color may be mixed.

In this arrangement, the colors may either be contained within box-like cavities having four upstanding walls, or a sheet of metal may be pierced and a portion of the metal on the underside and upon opposite sides or the sides and ends of the opening be turned or bent downwards to enclose the cake of color, the upper surface of which lies more or less in the plane of the upper surface of the plate.

In the first case the cavities radiate from a central portion enclosed by a circular wall, the space within which is provided with walled cavities or is otherwise adapted to contain one or more cakes of color.

The invention will now be described with reference to the accompanying drawings, in which:—

Fig. 1 is a perspective view of one form of color box according to the present invention.

Fig. 2 is a similar view of an alternative form of color box.

Fig. 3 is a perspective view of a further form of the invention.

Figs. 4 and 5 are respectively upper and underside perspective views of an alternative arrangement for holding the cakes of color within a circular outer container.

Referring to Fig. 1 of the accompanying drawings, 1 indicates the body portion of a paint box and 2 the hinged lid therefor.

Extending from end to end of the inside of the body portion 1 is a member 3 which is arranged in spaced relationship to and parallel with the forward vertical wall of the said body portion, and forms with said wall a compartment 4 for containing brushes.

Extending between the rear vertical wall of the body portion 1 and the rear surface of the member 3 is a series of strips 5 arranged in spaced relationship one to the other and spaced apart to form cavities, each of which cavities is divided into two portions by a partition 6, the portions 7 being designed to contain cakes of color and 55

the bottoms of the portions 8 forming paint mixing surfaces.

The partitions 6 are so arranged that when the cakes of color are placed in the aforementioned portions 7 of the cavities they are alternately disposed at the inner and outer ends of the latter.

In the modification shown in Fig. 2 the body portion 1 contains a pair of longitudinally extending parallel members 9, which form, along the middle portion of said body portion, a brush receptacle 9a and front and rear compartments along which are arranged in staggered formation frame-like bodies 10 which divide the said compartments into cavities 12 and 13.

15 The cavities 12 are designed to each contain a cake of color, and the bottom of each of the cavities 13 form a paint mixing surface.

It will be readily seen that when cakes of color are placed in the cavities 12 of the respective 20 front and rear compartments they are alternately disposed at the inner and outer ends of the said cavities.

According to the modification shown in Fig. 3 the box is circular and the body portion 14 there- 25 of is provided with a slip-on lid 15.

Disposed within the body portion 14 is a metal disc 16 upon which is soldered or otherwise suitably secured a strip 17 bent around a circular centre portion 18 to form a series of radially disposed pockets 19 for cakes of color, the intervening portions of the said disc forming paint mixing surfaces 20.

Secured within the aforesaid circular centre portion 18 is a disc 21 provided with perforations 22 each designed to receive a cake of color, and provided upon said centre portion are upwardly extending bifurcated lugs 23 designed to carry brushes.

Instead of the disc 16 being provided with 40 pockets 19 as just described, it may be provided with rectangular perforations 24 provided at their edges with downwardly extending projections 25 designed to engage and hold cakes of color in position when inserted into the said perforations, upwardly extending bifurcated lugs 26 being provided for the purpose of carrying brushes.

I claim:

1. An artist's color box comprising a body 50 portion; and means within said body portion for receiving spaced cakes of color and holding each of the latter adjacent a mixing surface provided within said means for the color from the respective cake one of said surfaces being located between each pair of color cakes and the body portion thereof.

2. An artist's color box comprising a body portion; a longitudinal member disposed within said body portion and in spaced relationship to one 60 of the walls thereof to form therewith, and with a part of the bottom of said body portion, a receptacle for brushes; transverse members forming with said longitudinal member and the wall opposite the first mentioned wall, cavities; and 65 partitions within said cavities which divide each of the latter into two parts, one of which parts serves to receive a cake of color, and the bottom of the other of which parts forms a mixing surface for the color from the respective cake.

70 3. An artist's color box, comprising a body portion; a longitudinal member disposed within said body portion and in spaced relationship to one of the walls thereof to form therewith, and with a part of the bottom of said body portion, a receptacle for brushes; transverse members form-

ing with said longitudinal member and the wall opposite the first mentioned wall, cavities; and partitions within said cavities which divide each of the latter into two parts, one of which parts serves to receive a cake of color, and the bottom 5 of the other of which parts forms a mixing surface for the color from the respective cake, the arrangement being such that the cakes of color when placed in said receptacles are alternately disposed at the inner and outer ends of said 10 cavities.

4. An artist's color box, comprising a body portion; a pair of members within said body portion, extending longitudinally thereof, and arranged in spaced relationship one to the other and to the front and rear walls of said body portion, to form respectively a receptacle for brushes, and front and rear compartments; members within said front and rear compartments which form series of cavities therein; some of 20 which cavities constitute receptacles for cakes of color, and the bottom of each of the other of which cavities a mixing surface on which color from a respective cake may be mixed.

5. An artist's color box, comprising a body portion; a pair of members within said body portion, extending longitudinally thereof, and arranged in spaced relationship one to the other and to the front and rear walls of said body portion, to form respectively a receptacle for brushes, and front and rear compartments; frame-like members within said front and rear compartments which form series of cavities therein, some of which cavities constitute receptacles for cakes of color, and the bottom of each of the other of 30 which cavities a mixing surface on which color from a respective cake may be mixed.

6. An artist's color box comprising a circular body portion; and means designed to hold a plurality of cakes of color radially within said body portion at each side of color mixing surfaces, there being one of the latter for each cake of color.

7. An artist's color box comprising a circular body portion; and a plate fitting within said body portion; a plurality of horizontally disposed substantially U-shaped bodies secured to the upper surface of said disc to form a series of radially arranged pockets open at their upper ends to each receive a cake of color, and extending along opposite sides of paint mixing surfaces upon said 55 plate, there being one such surface for each cake of color.

8. An artist's color box comprising a circular body portion; a plate fitting within said body portion, and a plurality of series of lugs projecting from the surface of said plate, each of said series being adapted to receive and hold in position a cake of color, the arrangement being such that said cakes, when so held in position, are each located radially within said circular body portion and along opposite sides of mixing surfaces for the respective cakes.

9. An artist's color box, in combination with a body, comprising means for supporting a plurality of cakes of color in spaced relation to each other, said means including respective color mixing surfaces adjacent to, and between each color cake.
